UNITED STATES PATENT OFFICE.

GEORGE L. THOM, OF WASHINGTON, DISTRICT OF COLUMBIA.

TRANSPOSING DEVICE FOR PLAYER-PIANOS.

1,010,983

Specification of Letters Patent.

Patented Dec. 5, 1911.

Application filed March 3, 1911. Serial No. 612,141.

To all whom it may concern:

Be it known that I, GEORGE L. THOM, a citizen of the United States, residing at Washington, in the District of Columbia, have invented certain new and useful Improvements in Transposing Devices for Player-Pianos, of which the following is a specification.

This invention relates to new and useful improvements in transposing devices for player-pianos and has for its object to provide a device capable of serving its function and at the same time avoiding any movement of the tracker-board or the terminal of the tubes leading from the pneumatics.

Another object, is to provide a device to transpose a piece of music and not necessitate the sliding of the tracker-board and thereby cause any improper alinement of the sheet of music.

Other objects will be apparent from the following specification, appended claims and, the drawings thereof, in which,

Figure 1. is an elevation of a tracker well 25 with the device applied thereto. Fig. 2. is a sectional view as on the line 2—2 of Fig. 1. Fig. 3. is a perspective view of the actuating means for the middle member. Fig. 4. is a plan view of the middle member, and Fig. 5. is a bottom view of the middle member.

Referring more specifically to the drawings, there is shown a tracker well of the usual construction in which is a tracker-board having the horizontal passages 11 and 35 the vertical passages 12 and secured to said tracker-board is a film of leather, fiber, or rubber 13 against which is intended to bear a sliding block or board 14, which is grooved on its upper and lower faces as at 15 and 40 16, said grooves being closed at their ends by the strips of batten 17. The grooves 15 are cut transversely across the upper face of the block 14 while the grooves 16 are cut diagonally across the under face thereof and 45 communication is had from one set of grooves to the other by the passages 18. Bearing against the under side of the block 14 is another block or board 19, provided with a film of material 20 similar to that of 50 13, the purposes of these two films of material being to create an air tight connection, yet permit a sliding movement of the member 14. The block 19 is provided with a set of vertical passages 21 which are in aline-

ment with the passages 12, and horizontal 55 passages 22, which communicate with the tubes 23 leading from the pneumatics, not shown. Secured to the ends of the block 14 are the racks 24 working in guides 25 and connected to the block as by a yielding connection, to permit any give incident to variations of the several parts, and said racks are controlled by pinions mounted upon the shaft 27 which is mounted in bearings in 60 the ends of the well. Adjacent to one of the pinions is a knurled thumb wheel 28 by 65 which the shaft and pinions are rotated.

The operation of the device is as follows; the perforated sheet of music is placed upon the spools and passed over the tracker board 70 as usual but the passage of air from the atmosphere to the pneumatics is as follows, through the perforation in the sheet, through the tracker-board passages 11 and 12, in the grooves 15 through the passage 18, 75 into the grooves 16, through the communicating passages 21 and 22, thence to the pneumatics. By the manipulation of the thumb wheel, shaft and pinions, the block 14 may be either advanced or retracted which 80 in turn will cause one or another of the diagonal grooves 16 to register with one or another of the passages 21 in the lowest block 19.

I claim,

1. A transposing device for pneumatically operated instruments comprising a bar having a plurality of ducts therethrough, a second bar in bearing relation therewith and having communicating ducts with those in 90 the first bar, and a plurality of individual diagonal grooves in one face of one of the abutting bars, and means for moving one of said bars laterally with respect to its longitudinal dimension to vary the relation of the 95 individual grooves and ducts of the abutting members.

2. A transposing device for player-pianos comprising a tracker-board, a block spaced therefrom, passages through said tracker-board and spaced block, a second block interposed between said tracker-board and spaced block and individual grooves spaced to correspond to the openings in the tracker board and spaced bar, in the opposite faces the 100 105 grooves in one face being non-parallel to those in the opposite face of said interposed block and having communication with one

another by air passages, said grooves being adapted to communicate with the passages in the tracker-board and spaced block.

3. A transposing device for player-pianos comprising a tracker-board, a block spaced therefrom, passages through said tracker-board and spaced block, a block interposed between the tracker-board and spaced board, grooves on the opposite faces of the interposed block, said individual grooves in one face being non-parallel to those in the opposite face and ducts connecting the grooves in said interposed block.

4. A transposing device for player-pianos comprising a board interposed into the passage for the tracker-board to the pneumatics of an instrument, grooves in said interposed board on the opposite faces thereof, said individual grooves on one face being non-par-

allel to those on the opposite face, ducts connecting said grooves and means to vary the position of said interposed board.

5. A transposing device for player-pianos comprising an interposed board within the passage for the tracker-board to the pneumatics of an instrument, grooves in the opposite faces of said board, the individual grooves on one face being non-parallel to those on the other, racks secured to said board, pinions meshing with said racks and means to rotate said pinions to vary the relation of the interposed board and passages with respect to said tracker-board.

GEORGE L. THOM.
